(57) **CLAIM**

The ornamental design for a wildlife feeder timer, as shown and described.

DESCRIPTION

FIG. 1 is a front, side and bottom perspective view of a wildlife feeder timer showing my new design;
FIG. 2 is a front view of the wildlife feeder timer of FIG. 1;
FIG. 3 is a side view of the wildlife feeder timer of FIG. 1;
and,
FIG. 4 is a further side view of the wildlife feeder timer of FIG. 1.

The broken lines showing indicia in FIGS. 1 and 2 are for illustrative purposes only and form no part of the claimed design.
